Patented Mar. 5, 1974

230,591

OPEN FACED SPINNING REEL

Arthur A. Underwood, Cincinnati, Ohio, assignor to
Brunswick Corporation, Skokie, Ill.

Continuation-in-part of abandoned design application Ser.
No. 184,992, Sept. 29, 1971. This application Apr. 9,
1973, Ser. No. 349,391

Term of patent 14 years

Int. Cl. D22—05

U.S. Cl. D22—25

Fig. 2

Fig. 1

Fig. 3

*Fig.4**Fig.5**Fig.6*FIG. 1 is a front end view of the open faced spinning reel;

FIG. 2 is a back end view;

FIG. 3 is a side elevation view;

FIG. 4 is a bottom elevation view;

FIG. 5 is a top view;

FIG. 6 is a side elevation view taken opposite to FIG. 3. This is a continuation-in-part of a design application Ser. No. 184,992, filed Sept. 29, 1971 and now abandoned.

I claim:

The ornamental design for an open faced spinning reel, substantially as shown and described.
